(57) **CLAIM**

The ornamental design for a target stand, as shown and described.

DESCRIPTION

FIG. 1 is a perspective front view of a target stand, showing our new design;

FIG. 2 is a perspective back view thereof;

FIG. 3 is a top view thereof;

FIG. 4 is a front view thereof;

FIG. 5 is a left side view thereof;

FIG. 6 is a back view thereof;

FIG. 7 is a right side view thereof; and,

FIG. 8 is a bottom view thereof.

Those portions of the figures shown in dotted lines form no part of my invention, but are included to show the context and environment of the invention.

1 Claim, 8 Drawing Sheets(56)
